BEVERAGE DISPENSING VALVE, OR SIMILAR ARTICLE

Richard T. Cornelius, Minneapolis, Minn., assignor to
The Cornelius Company, Anoka, Minn., a corporation
of Minnesota

Filed Sept. 5, 1968, Ser. No. 13,402

Term of patent 14 years

Int. Cl. D15—99
U.S. Cl. D94—3

FIG. 1 is a side elevational view of a beverage dispensing valve, embodying my new design, the opposite side having a reverse appearance.

FIG. 2 is a front elevational view thereof.

FIG. 3 is a top plan view thereof.

FIG. 4 is a bottom plan view thereof.

The essential features of the design reside in the portions shown in full lines.

I claim:

The ornamental design for a beverage dispensing valve, or similar article, substantially as shown and described.
